UNITED STATES PATENT OFFICE

SETH B. ATWOOD, OF ROCKFORD, ILLINOIS

METHOD OF MAKING COVERED-JOINT HINGE MEMBERS

Application filed July 5, 1927. Serial No. 203,429.

This invention relates to covered joint hinges such as are used for hanging automobile doors, and has more particular reference to the manufacture of the outer hinge member having the cover portion which forms an enclosure for one side of the knuckle joint.

The primary purpose of the present invention is to provide an improved covered joint hinge member and an improved method of making the same with a view to securing economy in the cost of manufacture and to producing a hinge member of this kind that will meet the commercial requirements.

In furtherance of these general objects my invention contemplates the provision of a blank having a profile or cross-section approximately that of the hinge member in its normal operative condition but having a part of its cover portion disposed at one side of its normal position to permit of slotting the knuckle by a milling operation and in subsequently bending the said cover part to its normal position overreaching the slotted side of the knuckle. This construction and method of manufacture are advantageous and desirable for reasons which will be apparent from the following description.

Referring to the drawings, Figure 1 is a side view of the hinge member blank;

Figs. 2 and 3 show first and second milling operations;

Fig. 4 is a side view showing the completed hinge; and,

Fig. 5 is a top view of the hinge shown in Fig. 4.

The manufacture of my improved hinge starts with producing a section approximately as shown in Fig. 1. This may be a rolled section or it may be produced by forging. In the event that the section is rolled the individual hinge member will be cut or sawed off to the proper width. It will be noted that this section is characterized by a flat strap portion 6, a knuckle portion 7 offset from the strap portion, an extension 8 providing a stop 9 against which the inside hinge member is adapted to strike for limiting the opening movement of the door, and an extension 11 at the outer side

of the hinge member providing a part of the cover portion which is adapted to overreach and cover the knuckle joint in the finished state of the hinge. The part 11 is disposed at one side of its normal position in order to permit of slotting the knuckle as by a milling operation to provide the knuckle bearing surfaces 12.

The knuckle portion 7 is slotted at its inner side preferably by means of a milling cutter such as indicated by the dotted line 13, Fig. 3. This slotting may be performed in any suitable manner although it is practical to use a milling cutter of approximately the diameter shown in comparison with the size of the blank profile and to mill to such depth as to leave a body thickness corresponding with that of the strap portion and gradually reducing or tapering toward the end of the cover portion as shown in Fig. 3. This milling operation leaves the bearing surfaces 12 parallel and accurately finished.

Subsequent to the slotting or milling operation the cover part 11 will be pressed or bent back against the knuckle proper so as to form a continuation of the outer curvature thereof and to overreach and enclose the knuckle joint. When this cover portion is properly pressed into position it will retain its shape and location because of its substantial integral connection with the blank from side to side thereof. Said part 11 will be pressed down against the curved end 14 of the knuckle proper, in this instance the extension 8 thereof, and the end 16 of said part 11 will be disposed adjacent to the stop 9.

Prior to the bending of the part 11 to its normal operative position a milling operation may be performed to finish the surfaces 14 and 15 in order to facilitate the making of a good joint between these parts. This milling operation may be performed by a form milling cutter which if desired may also be shaped to finish the stop face 9, the end 16 and a portion of the end 17 of the knuckle proper. Such operation is not however essential and, furthermore, substantially the same result may be obtained

by a forging or a coin-press operation. When finishing the surfaces 14 and 15 and others as just described I prefer that this operation should precede the slotting of the knuckle.

5. The knuckle will be drilled for the hinge pin or pintle and the cover portion may be crowned either by a grinding or a form milling operation, thus completing the manufacture of the outer hinge member.

10. My invention may be applied to the manufacture of either a three or a five knuckle hinge or for any suitable number of knuckles, the present drawing showing, 15 Fig. 6, the outer member of a five knuckle hinge.

I claim:

1. The method of making the outer member of a covered joint hinge consisting in forming a blank to a cross-section approximately that of the hinge member in its normal operative condition, said blank comprising a strap portion, a knuckle portion offset therefrom, an extension at the outer end of the knuckle portion having a stop abutment at its inner side, and a narrow extension at the outer end of the first mentioned extension adapted to form a part of the cover for the knuckle joint, slotting the 25 knuckle proper to provide bearing surfaces for the knuckle of the inner hinge member, and bending said narrow extension inwardly against the first mentioned extension of the knuckle proper.

35. 2. A one-piece covered joint hinge member of the character described the knuckle proper of which is slotted to provide finished knuckle bearing surfaces and the cover portion of which is free to be bent relative to the knuckle end and is integral therewith at its inner end from side to side thereof and has a press fit against the knuckle proper.

45. 3. The method of making the outer member of a covered joint hinge consisting in forming a body with a strap portion, a knuckle portion offset therefrom, the cross-section of the strap portion and the knuckle portion and the relation of one with respect to the other being the same as in the finished article, and a cover portion extending from the outer side of the knuckle portion in a position to permit of slotting the knuckle portion to form knuckles, slotting the 50 knuckle portion, and pressing the said extended part upon and with respect to the knuckle portion so that said part forms a curved continuation of the knuckle portion and serves to conceal the knuckle joint.

60. 4. The method of making the outer member of a covered joint hinge consisting in forming a body with a strap portion and a knuckle portion to the finished cross-sectional shape and relation one with respect to the other, and a cover part integral with

the knuckle portion at the outer side thereof and extending therefrom in a plane at an acute angle with respect to the adjoining outer face of the knuckle portion, slotting the knuckle portion to form knuckles, and bending the said cover part against the said adjoining face of the knuckle portion.

5. A one-piece covered joint hinge member of the character described, comprising a strap portion, a knuckle portion integral and offset to one side of the knuckle portion, the strap portion being slotted to provide spaced knuckles, and a thin-section cover portion extending across the outer end of the slotted knuckle portion reaching from side to side thereof and forming a continuation of the peripheral curvature of said knuckle portion, said cover portion being integral with the knuckle portion only at its inner end throughout the area of its thin cross-section.

6. The method of making the outer member of a covered joint hinge consisting in forming a blank to a cross-section approximately that of the hinge member in its normal operative condition, said blank comprising a strap portion, a knuckle portion offset therefrom, and a narrow extension adapted to form a part of the cover for the knuckle joint, slotting the knuckle proper to provide bearing surfaces for the knuckle of the inner hinge member, and bending said narrow extension inwardly against the knuckle proper.

7. The method of making the outer member of a covered joint hinge consisting in forming a blank to a cross-section approximately that of the finished hinge member to be produced, said blank comprising a strap portion, a knuckle portion offset therefrom, and a narrow extension destined to form a part of the cover for the knuckle joint, machining the knuckle and extension longitudinally so as to finish adjoining surfaces on the knuckle and extension to facilitate the making of a good joint subsequently between these parts, slotting the knuckle crosswise to provide bearing surfaces for the knuckle of the inner hinge member, and bending the extension inwardly against the knuckle so as to seat the finished surface of the extension on the finished surface of the knuckle.

8. The method of making the outer member of a covered joint hinge in one piece consisting in forming a blank to a cross-section approximately that of the finished hinge member, said blank comprising a strap portion, a knuckle portion offset therefrom, an extension at the outer end of the knuckle portion having a stop abutment at its inner side, and a narrow extension at the outer end of the first mentioned extension of sufficient length to terminate at the stop abutment when the same is subsequently bent against the knuckle to form a part of the

cover for the knuckle joint, slotting the knuckle to provide bearing surfaces for the knuckle of the inner hinge member, and bending the narrow extension inwardly against the first mentioned extension of the knuckle.

9. The method of making the outer member of a covered joint hinge in one piece consisting in forming a blank to a cross-section approximately that of the finished hinge member, said blank comprising a strap portion, a knuckle portion offset therefrom, an extension at the outer end of the knuckle portion having a stop abutment at its inner side, and a narrow extension at the outer end of the first mentioned extension adapted to form a part of the cover for the knuckle joint, milling the knuckle end of the blank longitudinally relative to the knuckle to provide finished surfaces on the inside of the narrow extension, and a cooperating finished surface on the outside of the first mentioned extension, the said narrow extension being then of sufficient length to terminate at the stop abutment when the said extension is subsequently bent against the knuckle, slotting the knuckle proper to provide bearing surfaces for the knuckle of the inner hinge member, and bending the narrow extension inwardly against the first mentioned extension of the knuckle so as to seat the finished inner surface of the narrow extension on the finished outer surface of the first mentioned extension.

35 In witness of the foregoing I affix my signature.

SETH B. ATWOOD.
